DRAWING FRAME CLEARER

Oscar F. Burman, Jr., Brockton, Mass., assignor
to Saco-Lowell Shops, Boston, Mass., a corpora-
tion of Maine

Application February 10, 1943, Serial No. 475,353

11 Claims. (Cl. 19—139)

A drawing frame of the character commonly used in connection with the preparation of textile fibers for spinning, usually includes four or five pairs of upper and lower rolls between which strands of roving are fed and by which they are drafted. In order to maintain the rolls comparatively free from lint and fly, a clearer cloth is customarily stretched across the upper surfaces of the entire series of top rolls where it rests lightly on them and wipes off the fly carried by them. Provision is made in these machines for adjusting the spacing of the rolls to accommodate different lengths of staple, and when such an adjustment is made it often is necessary, also, to lengthen or shorten the clearer to a substantially corresponding degree since, if the clearer is too long, it interferes with piecing up. Various expedients for accomplishing this object have been employed, such as splicing the clearer cloth or lapping it, as occasion may require, lacing the ends together, or connecting them by springs. All of these methods of adjusting the clearer to compensate for changes in the spacing of the rolls, however, are troublesome; and the present invention aims to devise a more satisfactory solution for this problem.

The nature of the invention will be readily understood from the following description when read in connection with the accompanying drawings, and the novel features will be particularly pointed out in the appended claims.

In the drawings,

Figure 1 is a plan view of a portion of a drawing frame constructed in accordance with this invention, some parts being shown in section;

Fig. 2 is a vertical, sectional view through the roll cover and the parts contained therein, the section being taken approximately on the line 2—2, Fig. 1;

Fig. 3 is a view similar to Fig. 2 but showing the rolls spaced more closely together and illustrating the clearer as adjusted to suit the requirements of this change in spacing; and

Fig. 4 is a vertical, sectional view on the line 4—4, Fig. 1.

The machine shown in the drawings comprises a series of bottom rolls 2 and cooperating top rolls 3, all arranged, supported and driven in a manner usual in machines of this type. The clearer cloth 4 is here made in an endless or belt form of such a width as to extend across substantially the entire lengths of the fiber working surfaces of the top rolls, and it is supported on front and rear clearer frame sections indicated, respectively, at 5 and 6. These frame sections

5 are overlapped, one upon the other. Each is of generally rectangular shape, the front section 5 having bars a and b at its forward and rearward edges, and the rear section 6 having bars c and d, respectively, at its corresponding edges, the space between said bars in each frame being open, except for end bars which connect them. The clearer cloth is threaded around these bars a, b, c and d, as shown in Figs. 2 and 3, and its ends are then brought together and sewed or fastened to each other in any convenient manner, butt stitching being preferred. This operation may conveniently be performed at the bar a.

It will be evident from an inspection of Fig. 2 15 that when the clearer has been installed in this manner it has a section e extending across and resting upon the upper surfaces of the entire series of top rolls 3. The other sections are idle at the moment, so far as the operation of clearing is concerned, but the fabric can be drawn around the bars at any time so as to present fresh surfaces to contact with the top rolls. It should also be observed that the clearer belt is disposed in a looped formation with two of these loops, 20 namely those in which the bars b and c are located, overlapped one upon the other. Also, that if the frames 5 and 6 are so arranged that one can be adjusted lengthwise of the belt relatively to the other, such adjustment will result in producing slack at one of the bars of the frame section that is moved and simultaneously taking it up at the same rate on the other bar of that section. For example, if the rear frame section 25 6 is moved to the left, Fig. 2, such movement of the bar d will tend to produce slack at the right-hand end of the belt, but the bar c will be moved simultaneously at the same rate and, consequently, it will take up the slack as fast as it is produced. Thus a constant tension on the belt will 30 be maintained notwithstanding the adjusting movement.

Provision is made for making the adjustment just described by forming a slot 7, Fig. 1, in the end of the rear frame section 6, passing a bolt 8 35 through this slot and threading it into the underlying end portion of the front section 5 and providing the same construction at the opposite end of the clearer. Thus by loosening the bolts the rear frame may be slid forward or backward 40 relatively to the front frame to the desired degree.

This adjustment is required only when a substantial change in the spacing of the drafting rolls is made, and the degree of adjustment of the clearer belt should be made to correspond in gen-

eral to the new adjustment of the rolls. As shown in Fig. 2, the rolls are mounted in bearing blocks 10, and all but the foremost of these blocks are mounted for adjustment toward and from the latter, the front block remaining fixed.

In addition to adjusting the extreme length of the span of the clearer belt, it is also desirable to adjust the length of the cover for the rolls. For this purpose the roll cover is made in front and rear sections, indicated at 11 and 12, respectively, and the latter section is slotted, as shown at 13, Fig. 1, to receive a bolt 14 carried by the front section 11, the same arrangement being provided at the opposite end of the cover. Threaded on each bolt 14 is a nut 15 cooperating with its respective bolt and with a washer 16 to clamp the two sections of the cover together. Thus by loosening the nuts at opposite ends of the cover, the rear section may be adjusted relatively to the front section to change the overall length of the cover to suit the requirements of different roll settings.

The front cover section 11 is reinforced at its forward corners by brackets 17 and the lower ends of these brackets rest in notches 18 cut in the front bearing blocks 10 at the opposite ends of the machine. Similarly, the rear cover section also is reinforced and stiffened by two hinge arms, one of which is shown in Figs. 1 and 2 at 20. This arm carries a pivot 21 resting in a pivot block 22 which is mounted on the roll stand for adjustment in the same manner as are the bearing blocks 10, and these two arms at opposite ends of the cover extend forward beyond the extreme overlap of the two cover sections, so that they add stiffness to the front as well as to the rear sections. This hinge mounting of the cover at its opposite ends permits it to be swung back into an open position affording free access to the rolls.

In order to support the clearer frame on the cover while still permitting that freedom of movement of the frame which is desirable, the nuts 15 for the bolts 14 are elongated, as shown in Figs. 2 and 3, and they extend through holes provided in lugs or ears that project from the opposite end bars of the forward frame section 5. One of these ears is shown at 23 in Figs. 1 and 4. Also, a washer 24, somewhat larger in diameter than the maximum diameter of the nut 15, is secured to the bottom of this nut by a screw 25. Bearing in mind the fact that the two frame sections are held together by the bolts 8, it will be evident that when the cover is swung upwardly, as indicated for example in dotted lines in Fig. 2, the nuts 15 will slide freely through the holes in the ears 23 for a very short distance until the washers 24 strike the lower faces of said ears, at which time they will pick up the entire clearer frame assembly and carry it with the cover. This connection not only holds the clearer frame loosely to the cover, but also determines the lateral and longitudinal position of the frame assembly in the cover.

It should be observed, however, that during the operation of the machine the nuts 15 do not support the clearer vertically but that, on the contrary, it rests by gravity on the top rolls 3. Also, that the front bars *a* and *c* of the two clearer frame sections are heavier than the rear bars *d* and *e*. This fact is useful in so distributing the weight of the clearer frame that the clearer belt bears with greater pressure on the front rolls than on the rear rolls, which is desirable because of the greater quantity of fly carried

by the forward rolls. The rear bar *b* of the front section also bears on the horizontal reach *e* of the clearer when the parts are extended, as shown in Fig. 2, and this fact is of advantage in applying pressure to that section of clearer belt in operative position, at an intermediate point in its length, where the pressure tends to be rather light. As the rolls are moved closer together, the bar *b* also assists the bar *d* in applying added pressure to the rearward end of the belt span.

In making a shortening adjustment of the cover and the clearer, the bolts 8 and 14 may be loosened, after which the mere act of moving the rear cover section 12 forward produces the necessary adjustment of it, and at the same time it acts on the rear clearer frame section to move it forward, both adjustments thus being made simultaneously. A slight correction of the cover adjustment may later be made by pulling it back a little in order to be sure that the rear end of the frame section 6 does not rub against the cover.

It will be evident from the foregoing that the invention provides a clearer construction in which the adjustment to suit different roll spacings can be made quickly and easily and in which, also, a relatively long length of clearer cloth is supported continuously in its operative position but is always maintained taut regardless of the adjustments.

While I have herein shown and described the preferred embodiment of my invention, it will be evident that the invention is susceptible of embodiment in other forms without departing from the spirit or scope thereof. The same problem with which this invention deals is present in any drawing mechanism including a set of upper and lower rolls between which strands of roving or the like are fed and by which they are drafted, if said rolls are mounted for adjustment to change the roll spacing. Obviously the invention is equally useful in all such mechanisms and they are therefore included in the term "drawing frame."

Having thus described my invention, what I desire to claim as new is:

1. In a drawing frame, the combination with a set of drawing rolls and means supporting them for adjustment to vary the spacing of said rolls, of a clearer belt for said rolls, and supports holding said belt in its operative position, said supports being relatively adjustable to change the overall length of the belt span and simultaneously to let out slack in one part of it and to take it up in another whereby the clearer is maintained taut notwithstanding said adjustments to conform to different roll spacings.

2. A drawing frame according to preceding claim 1, in combination with a cover for said rolls movable into open and closed relationship to them, said supports being mounted in and connected with said cover to be moved therewith when the latter is opened and closed.

3. In a drawing frame, the combination with a set of drawing rolls and means supporting them for adjustment to vary the spacing of said rolls, of a clearer belt for said rolls, and two sets of parallel bars around which said clearer belt is threaded in a looped formation with a portion of the belt overlapped upon another part thereof within the overall span of the belt, said sets of bars being relatively adjustable to change the

length of said span while maintaining the belt taut in all adjustments thereof.

4. In a drawing frame, the combination with a set of drawing rolls and means supporting them for adjustment to vary the spacing of said rolls, of a clearer belt for said rolls, and two sets of parallel bars around which said clearer belt is threaded in a looped formation with a portion of the belt overlapped upon another part thereof, one of said sets of bars being simultaneously adjustable lengthwise of the belt, whereby as fast as the movement of one bar produces slack in the belt, another bar takes it up.

5. In a drawing frame, the combination with a set of drawing rolls and means supporting them for adjustment to vary the spacing of said rolls, of a clearer belt for said rolls and means supporting said belt in its operative position, comprising front and rear frames each provided with front and rear horizontal bars, said frames being overlapped one upon the other, whereby the front bar of the rear frame is positioned ahead of the rear bar of the front frame, said belt being threaded around and supported on said bars and providing a loop section overlapped upon another part of the belt, said frames being relatively adjustable to vary the length of the belt span to suit different settings of said rolls, and means for securing said frames together in various adjusted relationships to form a clearer frame assembly supporting said belt in cooperative relationship to said rolls.

6. A drawing frame in accordance with preceding claim 5, in combination with a cover for said rolls mounted for swinging movement into open and closed relationship to them, and means connecting said frame assembly to said cover for rising and falling movement substantially therewith as the cover is open and closed.

7. A drawing frame in accordance with preceding claim 5, in combination with a cover for said rolls mounted for swinging movement into open and closed relationship to them, and means connecting said frame assembly to said cover and supporting said assembly loosely for swinging movement substantially with the cover and serving, also, to position said assembly both laterally and longitudinally in the cover.

8. A drawing frame according to preceding claim 5, in combination with a cover for said rolls comprising two sections overlapped one upon the other and adjustable to change the overall length of the cover to suit different roll spacings, means supporting said cover for swinging movement into open and closed relationship to said rolls,

means for locking said cover sections together in different adjusted relationships, and means connecting said frame assembly with said cover to position the assembly both laterally and longitudinally in the cover and also to lift said assembly out of its operative position when the cover is lifted.

9. A drawing frame according to preceding claim 5, in combination with a cover for said rolls comprising two sections overlapped one upon the other and adjustable to change the overall length of the cover to suit different roll spacings, means supporting said cover for swinging movement into open and closed relationship to said rolls, bolts for locking said cover sections together in various adjusted relationships, said bolts loosely supporting said clearer frame assembly for vertical movement with said cover and serving, also, to position said assembly both laterally and longitudinally in the cover.

10. In a drawing frame, the combination with a set of drawing rolls and means supporting them for adjustment to vary the spacing of said rolls, of a clearer belt for said rolls, and two sets of parallel bars around which said clearer belt is threaded in a looped formation with a portion of the belt overlapped upon another part thereof, a cover for said rolls comprising front and rear sections relatively movable to adjust the overall length of said cover to suit different roll settings, one of said sets of bars for supporting said clearer belt being adjustable simultaneously with the adjustment of said cover to change the length of span of said belt while maintaining it taut.

11. In a drawing frame, the combination with a set of drawing rolls and means supporting them for adjustment to vary the spacing of said rolls, of a clearer belt for said rolls, and two sets of parallel bars around which said clearer belt is threaded in a looped formation with a portion of the belt overlapped upon another part thereof, a cover for said rolls comprising front and rear sections relatively movable to adjust the overall length of said cover to suit different roll settings, and means supporting said cover for swinging movement into open and closed positions, and means connecting said cover with said frame assembly to support the latter loosely from the former, the rear section of said cover being so associated with said rear section of the clearer frame that a shortening adjustment of the cover automatically moves said rear frame section to produce a shortening adjustment of the clearer frame assembly.

OSCAR F. BURMAN, JR.
